UNITED STATES PATENT OFFICE.

EUGENE C. MAILLARD, OF LAKWOOD, OHIO.

THEATRICAL-MAKE-UP CABINET.

Application filed April 16, 1927. Serial No. 184,286.

In the theatrical profession, and especially in motion picture work where so much is done on "location", it frequently happens that actors and actresses are called upon to effect their make-ups under very unfavorable conditions and in the absence of suitable accommodations.

It is the fundamental purpose of my invention to provide a self-contained unit in the nature of a light and compact carrying case that is fitted with all the requirements for make-up purposes arranged in an especially convenient manner and so that, upon the case being opened, every piece of make-up material and implement is readily accessible, no one thing being in the way of another.

Another object of my invention is to incorporate in such a device an adjustable mirror, and electric lights that are individually adjustable with respect to the mirror so that every need in illumination and reflection may be realized.

A further object is to equip the outfit with an extension cord that is permanently connected to the electric lights and is preferably carried by a so-called "return" or self-rewinding drum so that the cord may be drawn out to any desired extent within its length and connected by means of a plug wherewith it is fitted to an electric light socket or wall receptacle, and when disconnected will be automatically retracted by the return drum.

Still further objects are to provide doors for closing the front of the case or cabinet that co-act with one another in such manner that all are retained closed by a locking of one door; and to incline the front of the cabinet downwardly and outwardly so that when the doors are opened they will tend to remain in such position by gravity, the inclination of the front also resulting in the make-up materials and implements carried by the doors being presented in a more natural and convenient position to the user.

The foregoing objects, and others which will hereinafter appear, are attained in the construction illustrated in the accompanying drawing wherein Fig. 1 is a perspective view of my improved make-up cabinet with the doors open and in readiness for use; Fig. 2 is a front elevation of the cabinet with the electric lights and mirror in the positions they occupy when the cabinet is closed; Fig. 3 is a front elevation of the cabinet with the

doors closed, and Fig. 4 is a right hand side elevation of the same.

The cabinet is designated 1 and to the forward edges of its side walls are hinged doors 2 and 3 while to its lower front edge is similarly connected what I shall term a horizontal door 4. It will be noted that the meeting edges of all the doors are complementarily rabbeted so that, when the doors are closed, the lower edges of the doors 2 and 3 overlie the upper edge of the door 4, while the free edge of the door 2 overlies the corresponding edge of the door 3. A lock 5, that is located at the top of door 2 adjacent its free edge, incorporates a bolt 5^a that is arranged to cooperate with a keeper (not shown) that is carried by the top of the cabinet so that when the bolt is projected by proper manipulation of the lock the door 2 will be locked in closed position, while the doors 3 and 4 will be also secured in closed position by reason of the fact that they are overlapped by the door 2.

A mirror 6 is supported through an extensible bracket or so-called "lazy tongs" 7 from the rear wall of the cabinet 1 adjacent its upper end, and also supported by said wall on opposite sides of the mirror and near the top of the cabinet are electric lamp sockets 8, the supports of said sockets incorporating pivots 8^a. Each of the sockets 8 is equipped with an electric lamp 9.

Supported within the upper rear portion of the cabinet is a return or automatic rewind drum 10, such as is used in automobile electric cigar lighters and other well known electrical appliances, and wound upon this drum is an electric light cord 10^a that is led out through an opening in the top wall of the cabinet, said opening being surrounded by a recess 10^b of ample size to accommodate the terminal member or plug 10^c wherewith the end of the cord 10^a is fitted. The recess 10^b is normally closed by a cover 10^d.

A tray 11 is preferably slidably supported within the cabinet 1 a suitable distance above the bottom wall thereof for the accommodation of comb, brush and other implements that are used in the process of making up, the doors also having holding means 12 for brushes, powder puff, etc. The door 2 carries receptacles 13 and the door 3 receptacles designated 14 for the accommodation of grease paint, spirit gum and other make-up materials.

Strips 15 of tape are attached by fasten-

ing means 16 to the inner side of the door 4 for holding in place upon said door braids 17 of different colors of hair, the fastening means 16 preferably being in the nature of snap fasteners so that the strips 15 may be readily detached to facilitate the replenishment of the supply of hair. Cans 18 of cold cream and powder may be accommodated within the lower portion of the cabinet.

10 As will be seen from Figs. 2 to 4 legs or protuberances 19 of rubber or the like are applied to the bottom of the cabinet, and suitably connected to the top wall of the cabinet is a handle 20.

15 When it is desired to use the cabinet, the same may be placed upon a stand or other suitable support, or it may be hung on a wall by engaging the handle 20 over a hook or nail. The lock 5 is next released and the 20 doors are swung to open position, after which the mirror 6 may be extended and adjusted, and the electric lamps 9 swung out to the desired positions. The cover 10^a is then swung from over the recess 10^b and the 25 cord 10^a is withdrawn and connected to an electric light socket or wall receptacle. Everything is now ready for immediate use, all materials and equipments being readily accessible. Due to the convenience 30 with which all items may be returned to their proper places within the cabinet just as soon as the user is through with them, the outfit is ready at any moment to be closed. This is very important in cases 35 where a performance is concluded only a little while before train time, or where shifts have to be made in a hurry on location, as, under such circumstances, it is only necessary to release the cord 10^a (in case the 40 lights have been used) and allow it to be retracted by the return drum 10, swing the lamps 9 into the cabinet and close the doors, when the outfit is ready to be carried away.

The receptacles carried by the opposed 45 doors are so arranged as to avoid interference when the doors are being shut, and to fit within the cabinet to the best advantage when the doors are closed.

Having thus described my invention what 50 I claim is:

1. A device of the character set forth comprising a cabinet having an open front, a door hinged to the lower edge of the cabinet and arranged to close the lower portion 55 of said open front, doors hinged to the lateral edges of the cabinet for closing the upper portion of the open front, the lower edges of the latter doors overlapping the upper edge of the first mentioned door, and 60 holders for make-up materials carried by the inner sides of said doors.

2. A device of the character set forth

comprising a cabinet having an open front, doors hinged to the cabinet for closing said open front, holders for make-up materials carried by the inner sides of said doors, a mirror supported within the cabinet, and electric light sockets adjustably supported adjacent the mirror.

3. A device of the character set forth 70 comprising a cabinet having an open front, doors hinged to the cabinet for closing said open front, holders for make-up materials carried by the inner sides of said doors, a mirror supported within the cabinet by 75 means of an extensible bracket, and electric light sockets adjustably supported on opposite sides of the mirror and adapted to be swung into and out of the cabinet.

4. A device of the character set forth 80 comprising a cabinet having an open front, doors hinged to the cabinet for closing said open front, a mirror adjustably supported within the cabinet, illuminating means similarly supported adjacent the mirror, and 85 an electric conductor in the nature of an extension cord connected to the illuminating means and adapted to be withdrawn from and recoiled within the cabinet.

5. A device of the character set forth 90 comprising a cabinet having an open front, doors hinged to the cabinet for closing said open front, a mirror adjustably supported within the cabinet, electric light sockets similarly supported adjacent the 95 mirror, a return drum housed within the cabinet, and an electric conductor in the nature of an extension cord wound on said drum and having electrical connection with the electric light sockets.

100 6. A device of the character set forth comprising a cabinet having an open front, doors hinged to the cabinet for closing said open front, a mirror supported within the cabinet, electric light sockets supported adjacent the mirror, and an electric conductor in the nature of an extension cord connected to the electric light sockets and adapted to be withdrawn from and retracted into the cabinet, said cord being fitted with an attaching plug, the cabinet having an outlet 105 opening for the cord surrounded by a recess for the plug.

110 7. A device of the character set forth comprising a cabinet having an open front, a mirror supported within the cabinet, illuminating means adjustably supported adjacent the mirror, means for closing the open front of the cabinet, and holders for make-up materials carried by said closing 115 means.

In testimony whereof, I hereunto affix my signature.

EUGENE C. MAILLARD.
